DESIGN FOR AN OIL BURNER BOILER

John D. Landerman, Allston, Mass.

Application February 11, 1944, Serial No. 112,538

Term of patent 7 years

(Cl. D81—2)

To all whom it may concern:

Be it known that I, John D. Landerman, a citizen of the United States, residing at Allston, in the county of Suffolk and State of Massachusetts, have invented a new, original, and ornamental Design for an Oil Burner Boiler, of which the following is a specification, reference being had to the accompanying drawing, forming a part thereof.

Figure 1 is a side elevational view of an oil burner boiler, showing my new design;

Figure 2 is a front elevational view thereof;

Figure 3 is a side elevational view showing the other side of the oil burner boiler from that shown in Figure 1.

I claim:

The ornamental design for an oil burner boiler, as shown.

JOHN D. LANDERMAN.
